Attorneys

UNITED STATES PATENT OFFICE.

WILLIAM SCHMID, OF BRONSON, MICHIGAN.

CARBURETOR.

Application filed August 12, 1921. Serial No. 491,657.

To all whom it may concern:

Be it known that I, WILLIAM SCHMID, a citizen of the United States of America, residing at Bronson, in the county of Branch 5 and State of Michigan, have invented certain new and useful Improvements in Carburetors, of which the following is a specification, reference being had therein to the accompanying drawings.

10 This invention relates to carburetors, and my invention includes two forms of carburetors, one of which may be attached to the side of an engine block to communicate with the cylinders thereof, and the other 15 form of carburetor may be connected to the usual intake manifold of an internal combustion engine. In either the vertical or horizontal types practically the same novel features are embodied for controlling the 20 admixture of gas and air, and while the carburetor has been especially designed for utilizing gasoline as a fuel, it may be used for atomizing kerosene or other fuels.

25 The primary object of my invention is to provide a carburetor, wherein the throttles, valves and other controlling devices are located axially of the carburetor and the majority of said controlling devices made of pressed sheet metal, thus reducing the 30 weight of the carburetor and the cost of producing the same.

Another object of this invention is to 35 provide a carburetor including a sleeve air throttle articulated with a tube for movement in synchronism, and associated with the tube is an adjustable choke member which, prior to constant use of the carburetor, may be adjusted to provide a lean or 40 rich admixture of gas and air, particularly for idling and starting purposes of an engine.

The above are a few of the many objects 45 that may be attained by my invention and in describing the two forms of carburetors, it is to be understood that the construction and arrangement of parts, in either form of carburetor, may be changed without departing from the spirit of the invention, as defined by the appended claim.

50 Reference will now be had to the drawings, wherein—

Figure 1 is a vertical sectional view of one form of carburetor;

55 Fig. 2 is a horizontal sectional view, on a smaller scale taken on the line II—II of Fig. 1;

Fig. 3 is a plan of a sleeve air throttle and its actuating member, and

Fig. 4 is a vertical longitudinal sectional view of another form of carburetor. 60

Reference will first be had to Figs. 1 to 3 inclusive showing what may be considered as the vertical type of carburetor, and the reference numeral 1 denotes a float chamber having a side wall thereof provided 65 with a fuel inlet connection 2 adapted to communicate with a fuel tank and receive fuel therefrom by gravity. The connection 2 serves as a valve body for a needle valve 3 and adjacent said needle valve is a pivoted 70 float arm 4 provided with a conventional form of float 5, said float and float arm controlling the needle valve 3. The valve 3 may be opened by pressure of gasoline or other fuel against the needle of said valve 75 and after a predetermined quantity of fuel is accumulated within the float chamber the float arm 4 closes the needle valve 3 to prevent flooding of the float chamber.

On top of the float chamber 1 is a cover 6 provided with a central depending nozzle chamber 7 terminating in a stem 8 which has a threaded portion 9. The nozzle chamber 7 and its stem 8 correspond in depth to the float chamber 1 and the threaded portion 9 extends through an opening 10 in the bottom wall of the chamber 1 and is provided with a nut 11, said nut clamping the bottom wall of the float chamber against the stem 8 and the upper edges of said float chamber against 85 the cover 6.

The nozzle chamber 7 is of inverted conical shape, that is, it tapers inwardly from the cover 6 to the stem 8 and axially of the stem is a nozzle 12 communicating with a 90 lateral passage 13 in said stem, said lateral passage communicating with the float chamber 1 and permitting fuel in the nozzle to assume the same level as fuel in the float chamber. The nozzle 12 is tubular, to serve 95 as a guide and the upper end of the nozzle has a single small orifice 14.

In the stem 8 is a drain passage 15 permitting any fuel that may enter the bottom of the chamber 7 to drain from the carburetor. 100

The upper face of the cover 6 has an annular flange 16 about the open end of a nozzle chamber 7 and fitted over said flange is a cylindrical air intake member and throttle 110 seat 17 preferably made of pressed sheet metal. The air intake member 17 has its

cylindrical wall provided with a plurality of wide openings 18 and its lower edge with a lateral flange 19 which may be secured to the cover 6 by screws 20 or other fastening means. The air intake member 17 communicates with the nozzle chamber 7 and has a tapering depending portion 21 terminating in a sleeve 22 which extends into the nozzle chamber 7 in spaced relation to the walls of said chamber and the nozzle 12 therein. The sleeve 22 is a fixture within the nozzle chamber and for any air to enter said sleeve it is necessary for the air to pass through the openings 18, downwardly in the nozzle chamber 7 and then into the lower end of the sleeve.

Secured to the cover 6 by screws 23 or other fastening means are the apertured inwardly projecting lugs 24 of a cylindrical carburetor body 25, said body being fitted on the cover 6 and cooperating with the float chamber 1 in providing a cylindrical carburetor structure. The side wall of the carburetor body 1 has a large air intake connection 26 and the top wall of the carburetor body has openings 27 to accommodate fastening means by which the carburetor body may be connected to the intake manifold of an internal combustion engine. In addition to the openings 27 there is a large central opening 28 adapted to communicate with the intake manifold so that fuel may pass from the carburetor to the engine. Depending from the top wall of the carburetor is a guide 29 for a sleeve air throttle 30 which has its upper end sliding in the guide 29. The lower end of the sleeve air throttle is adapted to either communicate solely with the tapered portion 21 of the air intake member 17 or with said tapered portion and the interior of the carburetor body 25. The sleeve air throttle is preferably made of sheet metal and has its lower end rolled, as at 31, so as to seat on the upper edge of the air intake member and throttle seat 17. When so seated the sleeve air throttle cannot receive air direct from the air intake connection 26, but may receive air indirectly, as will hereinafter appear.

The sheet metal sleeve air throttle is formed with a flange 32 intermediate its ends and engaging said flange, at diametrically opposed points are the forked heads 33 of a set of arms 34 mounted on a rock shaft 35 extending transversely of the carburetor body 25. One end of the rock shaft 35 may have a crank 36 for suitable connections so that the sleeve air throttle 30 may be raised and lowered in its guide 29 from a remote point.

Mounted in the flange 32 as shown in Fig. 1 are the ends of radially disposed arms of a spider 37 within the sleeve air throttle 30 for movement in synchronism therewith and attached to the spider 37 by a nut 38 or other

fastening means, is the upper apertured end 39 of a tube 40 which extends axially of the sleeve 22 and is slidable on the nozzle 12. The tube 40 has its outer wall tapered inwardly from a middle portion of the tube to the ends thereof, the upper inwardly tapered end not interfering with passage of air from the sleeve 22, and the lower inwardly tapered end having circumferentially arranged and angularly disposed openings 41, said openings being directed upwardly at an angle to the axis of the tube in proximity to the upper end of the nozzle 12, so that air may readily commingle with fuel.

Slidable in the sleeve 22 against the walls thereof is a tubular adjustable choke member 42, said member being guided by the sleeve 22 and having its upper end inwardly rolled to provide an annular bead or restriction 43 in proximity to the inwardly tapered walls of the lower end of the tube 40. By shifting the tubular choke member 42 within the sleeve 22 the passage between the tube 40 and the annular restriction 43 may be increased or decreased in area. As shown in Fig. 1 the annular passage is very small and in some instances it may be substantially closed by the restriction 43 engaging the tube 40. From this extreme position the adjustable choke member 42 or tube 40 may be shifted, relative to each other, so that from a closed passage such passage may be gradually opened and increased in area until there is an extreme wide open position of the choke member.

For adjusting the choke member 42 said member has its lower end provided with an upstanding outside arm 44, that is, the arm extends upwardly between the walls of the nozzle chamber 7 and the walls of the sleeve 22. With the choke member made of sheet metal it can be easily formed with the arm 44 and the upper end of said arm can be furthermore formed to receive the pintle 45 of a curved crank 46 on the end of a rock shaft 47, journaled in a long bearing 48, carried by the carburetor body 25. The bearing 48 extends inwardly from the wall of the carburetor body 25 and through one of the openings 18 of the air intake member and throttle seat 17. On the outer end of the rock shaft 47 may be mounted a crank 49 by which the choke member may be actuated and set in a defined position relative to the sleeve 22 and the tube 40.

Figure 1 shows the parts of this form of carburetor in the position assumed when the associated engine is idling. The reduction of atmospheric pressure in the sleeve air throttle 30, which is closed, causes air to be drawn in the connection 26 into the carburetor body 25, through the openings 18 on the air intake member 17, downwardly in the nozzle chamber 7 and then upwardly in the choke member 42. A quantity of the

air will pass through the openings 41 of the tube 40. The air entering the openings 41 will mix with fuel lifted from the nozzle 12 and such mixture will pass out of the nozzle 39 into the sleeve air throttle 30. It is in this throttle that the atomized fuel will commingle with the air passing through the openings 41 and between the tube and the choke or restriction 43, the air 10 commingling with the atomized fuel and passing on to the engine. The admixture of fuel and air may be regulated, according to the nature of the fuel, by the choke member, so that there will be either a rich or 15 lean mixture passing through the throttle 30. As the throttle is raised air from the connection 26 may pass in to the throttle under the lower end thereof and by reason of the tapered wall of the tube 40 being raised 20 relative to the choke member 42 there will be a larger passage between the tube and the choke member for air to pass upwardly through the choke member and meet the air entering the throttle 30 from lateral directions.

I attach considerable importance to the fact that the carburetor is devoid of a great many parts which require adjustment in order to place the carburetor in an operative 30 condition. It is only necessary to properly place the choke member when first placing the carburetor in operation for a specific fuel, and then the throttle 30 is operated in the usual manner to control the speed of the engine. In changing from one fuel to another it may be necessary to adjust the choke member for desired results, or in some types of automobiles the choke operating 35 means may be articulated with other devices for accelerating or other purposes.

Reference will now be had to Fig. 4 showing what may be considered as the horizontal type of carburetor and in a great many respects it is similar to the vertical type. 45 For instance, there is a float chamber 50 having a fuel inlet valve 51 controlled by a float 52 in the float chamber 50. The float 52 in this instance is crescent or semi-circular in shape, in contradistinction to the circular form shown in Fig. 1, so as to provide clearance for angularly disposed parts in the float chamber 50. On the float chamber 50 is a cover 53 having an angularly disposed nozzle chamber 54 provided with a vertical stem 55 axially of the float chamber 50 and connected thereto by a screw 56. The nozzle chamber 54 communicates with the float chamber by a depending apertured extension 57 which supports the float arm 58 of the float 52. The nozzle chamber has a side wall thereof enlarged, as at 59, and supported by the cover 53 and formed integral with the nozzle chamber is an air intake member throttle seat 60 having the sleeve 61 extending into the nozzle cham-

ber about a nozzle 62 supported within said chamber in communication with the apertured extension 57, so that fuel within the float chamber 50 may rise to the same level within the nozzle 62.

Suitably mounted on the cover 53 and connected to the float chamber 50 is a transversely disposed body 63 which has one side thereof provided with an air intake connection 64 and the opposite side thereof with a manifold connection 65, which as set forth in the beginning, may be connected to the side wall of an engine block or cylinder, instead of a manifold.

At the inner end of the connection 65 is an angularly disposed tubular guide 66 coaxial with the nozzle chamber 54, so that the guide 66 may have a sleeve air throttle 67 to seat on the air intake member 60. The seating end of the air throttle 67 has a spider 68 supporting a choke member 69 which is slidable in the sleeve 61 and adjustable in synchronism with the air throttle.

In order that the air throttle 67 may be shifted on the guide 66, to and from the air intake member 60, the carburetor body 63 is provided with a rock shaft 70 and on said rock shaft within the carburetor body, is a crank 71 engaging a flange 72 of the air throttle 67. On the outer end of the shaft 70 is a crank 73.

Slidable on the nozzle 62, within the choke member 69, is a hollow tapering tube 74 provided with a series of circumferential and radially disposed openings 75 in proximity to the orifice of the nozzle. The upper end of the tube pin 74 has an aperture 76 affording a secondary nozzle and this end of the tube is suitably fixed to a perforated tube 77 axially of the guide 66 and the air throttle 67. The upper end of the perforated tube 77 is connected to a rod 78 extending through an adjustable guide 79 screwed in the top of the carburetor body 63. On the outer end of the rod 78 is an inverted cup shaped head 80 confronting a cup 81 of the guide 78 and extending into the cup 81 and the cup shaped head 80 is a coiled expansion spring 82 encircling the rod 78. The expansive force of this spring holds the tube 74 normally elevated with the guide 79 limiting the outward movement of the rod 78.

A pivoted arm or cam member 83 supported from the manifold or cylinder connection 65 bears against the head 80 and permits of said head being depressed, by any suitable operating mechanism, for lowering the tube 74 on the nozzle 62. From a remote point it is therefore possible to regulate the carburetor for a constant initial lean or rich admixture of air and fuel, and to which explosive mixture additional air may be admitted from between the air intake member 60 and the air throttle 67.

The perforated tubes 77 will emit atomized fuel from all sides.

From the foregoing it will be observed that many parts of the horizontal carburetor are similar to parts within the vertical carburetor, the main differences being that in the horizontal carburetor, the choke member is movable with the air throttle independent of adjustment of the tube, whereas in the vertical carburetor the tube is movable with the air throttle and the choke member has an independent adjustment.

It is thought that the operation and utility of both forms of carburetors will be apparent without further description and while in the drawings there are illustrated the preferred embodiment of my invention, it is to be understood that the structural elements are susceptible to such variations

and modifications as fall within the scope of 20 the appended claim.

What I claim is:—

A carburetor having a nozzle chamber with a nozzle therein, an air intake member over said nozzle chamber and having a 25 sleeve about said nozzle, an adjustable tubular throttle movable to and from said air intake member, an apertured tube supported axially of said throttle and slidable on said nozzle, a choke member slidable in the 30 sleeve of said air intake member, and means in said air intake member and extending into said nozzle chamber and to the lower end of said choke member adapted for adjusting said choke member in the sleeve of 35 said air intake member.

In testimony whereof I affix my signature.

WILLIAM SCHMID.
